MAKE-UP JACKET

Wilma C. Oakvik, Minneapolis, Minn.

Application June 28, 1951, Serial No. 233,965

1 Claim. (Cl. 2—50)

1

This invention relates to make-up jackets for use by ladies to protect their dresses from becoming soiled during the application of facial cosmetics.

It is customary for ladies to complete their attire before applying lipstick, rouge, powder and other facial cosmetics, because to don a dress over the head after applying facial cosmetics results in soiling of the dress by contact with the facial make-up and also disturbs the make-up, thus necessitating restoring the make-up.

The primary object of this invention is to provide a loosely fitting jacket for a lady to wear which completely overlies the shoulders and the upper portions of a dress to protect the dress from becoming soiled during the application of facial cosmetics.

It is another object of this invention to provide a make-up jacket having a body of sufficient size to fit loosely on the body of a wearer and also providing overlapping inner edges at a medial opening in its front thus permitting freedom of body movements of the person wearing the jacket in applying facial cosmetics with the inner edges of the jacket remaining in overlapped relationship.

It is another object of this invention to provide a make-up jacket including sleeves having overlapping inner edges at an opening in the front of the jacket, the sleeves and the body of the jacket being of sufficient size to fit loosely on the body of a wearer of the jacket thus permitting freedom of body movements in applying facial cosmetics with the inner edges of the jacket remaining in overlapped relationship.

With the foregoing and other objects in view, reference is now made to the following specification and accompanying drawings in which the preferred embodiments of the invention are illustrated.

In the drawings:

Figure 1 is a front view of the make-up jacket constructed in accordance with the invention.

Figure 2 is a rear view thereof.

Figure 3 is a sectional view taken on line 3—3 of Figure 1, showing the type of seam employed at all edges of the jacket.

Figure 4 is a fragmentary view of a modified construction of a sleeve used with the jacket of Figures 1 and 2.

Referring to the drawings by character of reference, 10 is the make-up jacket which comprises a rear panel 12 and opposite side panels 14 and 16 forming the front of the jacket 10. The opposite edges of the rear panel 12 are

2

turned inwardly and the abutting edges of the panels 14 and 16 are turned inwardly and then these abutting inturned edges of the rear panel 12 and the side panels 14 and 16 are stitched together as at 18. At the opposite upper sides of the rear panel 12, three-quarters length sleeves 20 have their inner edges turned in to abut turned in edges of the rear panel 12 and side panels 14 and 16 respectively and the abutting edges of the sleeves and panels are stitched together.

The rear panel 12 and side panels 14 and 16 are of sufficient size to provide a garment of a size which will fit loosely on the body of women 15 permitting freedom of body movement for the wearer of the jacket 10. The sleeves 20 are oversized in relation to the size of the ladies' arms wearing the jacket 10 so that there is great freedom of movement for the arms in the sleeves 20. 20 There is a neck opening 22 provided by the rear panel 12 and the opposite side panels 14 and 16. Also a medial opening 24 is formed between the inner edges 26 and 28 of the side panels 16 and 14 respectively which extends from the neck 25 opening 22 to the bottom edge of the side panels 14 and 16. The inner edges 26 and 28 of the side panels 16 and 14 respectively normally overlap in a substantial overlapped separated relation as at 29 when worn by the ladies using the make-up jacket 10. The loosely fitting body of 30 the jacket 10 and also the loosely fitting sleeves 20 permits a lady wearing the jacket 10 to apply facial cosmetics with great freedom of body and arm movements with the overlapped inner edges 26—28 remaining in their overlapped relationship and as a consequence there is no likelihood 35 of the lady wearing the make-up jacket soiling her dress.

The inner edges 26 and 28 of the panels 16 and 14 respectively, the bottom edges of the rear panel 12 and side panels 14 and 16, also the edges of the neck opening 22 as well as the lower edge of the sleeves 20 are lapped over on the outside of these panels and on the outside of the sleeves as at 30. Then a narrow trim 32 overlies 40 all of these lapped edges 30 with a portion 34 of the trim 32 extending over the outside surface of the panels and sleeves as at 36. A hidden stitch means 38 secures the trim to the lapped portion 30 of the panels etc. and the abutting portion of the panels and sleeves. A second stitch means 40 secures the extended portion 34 of the trim 32 to the abutting portion of the panels etc. The trim 32 overlying these lapped edges 50 30 of the panels and sleeves etc. prevents ravel-

ing of the material of the panels and sleeves and also provides a neat appearing jacket 10.

In Figure 4 sleeve 50 is provided with a relatively short upwardly extending slit 52 formed at its lower edge, and the slit 52 in this sleeve is to provide additional freedom of movement for the arms of a lady wearing the loosely fitting jacket with the loosely fitting sleeves.

The jacket 10 being of a size to loosely fit the body of a wearer thereof and providing overlapping edges 26 and 28 of the side panels 16 and 14 when being worn by a lady, all fastening means for securing the opening together at the front of the jacket may be eliminated.

The jacket may be made of cotton, gingham, percale, or any other appropriate materials.

While the jacket has been described for make-up purposes, the same may be used to protect one's garments while having a hair shampoo. Furthermore, such changes in structure and design as come within the scope of the appended claim may be resorted to if desired without departing from the spirit of the invention.

Having thus described the invention, what I claim as new and desire to secure by Letters Patent of the United States is:

A make-up jacket comprising in combination a body portion consisting of a back panel and front panels and including sleeves, the front panels of the body portion arranged with their inner edges disposed in substantially overlapped separated relationship with respect to each other to provide an overlapped opening at the front of

the make-up jacket, the bottom most edge of the overlapped portions of the body being as wide as the width of the major length of the overlap, the body portion being of sufficient size to be loosely worn on the body of a wearer of the make-up jacket, the said sleeves being of sufficient size to be loosely worn on the arms of the wearer of the make-up jacket, each of the sleeves having a relatively short upwardly extending slit formed at its lower edge to enhance freedom of movement of the arms of the wearer of the make-up jacket, the loosely fitting body of the make-up jacket in combination with the loosely fitting slit sleeves permitting relatively great body movement by the wearer of the make-up jacket so that the wearer of the make-up jacket may apply facial cosmetics with facility and whereby the overlapped inner edges of the body portion remain in their substantially overlapped separated relationship with respect to each other.
